UNITED STATES PATENT OFFICE.

HENRY A. HANSEN, OF STURGEON BAY, WISCONSIN.

STAND FOR SUPPORTING WASHTUBS, TABLE TOPS, AND THE LIKE.

Application filed March 15, 1926. Serial No. 94,920.

This invention primarily relates to stands for supporting washtubs, table tops and the like; it has especial reference to the so-called collapsible or folding type of stand; and it 5 involves certain unique features.

An object of the invention is to provide a stand of the kind specified which can be manufactured and sold at a comparatively low figure and which, at the same time, is of 10 simple construction and conveniently handled.

The main object of the invention is to provide a folding stand which, in use, will be entirely stable by reason of its construction 15 and the assemblage of its parts; and which, also, includes means for adjusting the supporting components so that the plane at which the tub is to be supported may be raised or lowered, and tubs of various diameters 20 may be mounted and effectually held. Withal, the components of which the structure is made are such as to be folded into compact form for shipment, storage, etc.

In order that the invention may more readily be comprehended, I have herein revealed the same in three embodiments; it being understood, however, that these are illustrative, that the structure may be otherwise embodied or utilized, and that the illustrated embodiments 30 are susceptible of a wide range of modification, and variation without departing from the spirit of my inventive-concept or sacrificing any of the underlying principles or salient features thereof.

35 In these drawings:

Figure 1 is a view in perspective showing a folding stand with my inventive-concept embodied therein and with a tub or the like indicated in dotted lines in the position it 40 occupies when sustained by the stand;

Figure 2 is a view in elevation of the stand showing the parts in full lines for supporting the tub in one position and, in dotted lines, the position of those parts when adjusted to 45 support the tub in a lower plane, or a tub of a different diameter;

Figure 3 is a view in elevation of the stand when folded;

Figure 4 is a fragmentary view, in sectional elevation and on a large scale, of a device for adjusting the components of the structure;

Figure 5 is a view in perspective, and somewhat fragmentary, of an element forming 55 a part of the adjusting device;

Figure 6 is a view, in perspective, of another embodiment of my invention, being a modification of the structure shown in Figs. 1 and 2;

Figure 7 is a sectional view of a component 60 of the adjusting device of the stand shown in Fig. 6; and

Figure 8 is a similar view of another embodiment comprising, in this instance, three supporting legs instead of four, as in the 65 other two embodiments.

Referring to the drawings, and to the embodiment of the invention illustrated in Figs. 1 to 5, the reference-character 1 designates a tub or similar receptacle to be mounted in 70 my improved stand.

This stand, preferably and as shown in Fig. 1, for instance, includes four supporting legs or elements 2, made of any appropriate material and of required form and dimensions. Each of these, adjacent its upper 75 end, is provided with a series of notches 3, in one or another of which the tub 1 is adapted to be seated and by which it is held.

Disposed between the set of legs, and preferably intermediate of their ends, is a pivot-block or element 4, shown in this instance as square and provided with a boss 5 upstanding from its upper surface. Each leg is pivotally secured, as by a screw or headed pin 6, to the block and on which it fulcrums in being adjusted from its "closed" position, shown in Fig. 3, to its "open" position, shown in Figs. 1 and 2.

Threaded into the pivot-element 4 is an 90 adjusting-member or screw 7, provided on its upper end, preferably and as shown, with a rounded head 8. The screw is preferably knurled, as at 9, to facilitate its rotative movement.

Pivoted or otherwise connected, as at 10, to each leg, above the plane of the pivot-block 4, is a link 11 which, at its opposite end, is pivoted to a link-connecting element or block 12 which, in this instance, is shown as square, as being stamped into shape, and as provided, at each of its corners, with a cut-out or slot 13 constituting what I shall herein call a link-guiding and link-locking instrumentality; it being seen that each link 11 extends from its pivot-point 14 in the element 12 through its respective cut-out 13, and that it is free to move therein though, by reason of the dimension of the cut-out, the link is guided by its engagement with the 110

side wall 15 of the block and the edge 16 of the cut-out. The height of the block 12 is such as to permit its movement to a considerable degree without moving the link out of position in the cut-out.

5 As shown in Fig. 5, the block is provided with a central aperture 17 of diametral dimensions less than the head 8 so that, as shown for instance in Fig. 4, the head may engage in the aperture 17 when the block 12 is seated in operative relation with respect to the adjusting-member 7.

10 It is to be understood that where I have herein used the term "link", it refers to any appropriate connecting element, such as an arm or similar instrumentality, adapted to connect the block 12 with a supporting leg and facilitate the adjustment of the leg with respect to the other parts of the structure.

15 20 More readily to accommodate the block or element 12 when the stand is folded, as shown in Fig. 3, the upper extremities of the legs are cut away at one side, as at 18.

25 Operation: For packing, storage, shipping, etc., the stand would be folded or collapsed, as shown in Fig. 3. In this situation, the connecting-element 12 will occupy a position adjacent the upper extremities of the legs and in the cut-outs 18 in the upper ends 30 of the legs; and the links will then occupy an approximately vertical position and parallel with the legs, which also will be substantially parallel to each other. In this position, the connecting-element 12 will be considerably removed from the head 8 of the 35 adjusting-screw 7.

40 When the stand is to be used, the components of the structure are manipulated so that the legs will each occupy a position at an angle to the horizontal, the connecting-element will rest on the headed adjusting-screw, as shown in Figs. 1, 2 and 4, and the links will occupy an approximately horizontal plane. That is to say, that will be the 45 position when the legs are spread to their limit and the connecting-block 12 occupies its lowermost position. If, however, it be desired to position a tub in a higher plane, the parts are adjusted, through the screw 7, so as to raise the connecting-block 12 to a higher 50 plane and, through this and the links, the legs will be adjusted relatively so that their upper extremities will be brought closer together. The notches 3 are in series so that, 55 if the position of the parts is such that one set of notches on the several legs is not at the right plane, the tub can be placed in the set of notches in the next higher or lower plane. At first, an approximate positioning 60 of the tub in the notches is effected so that the proper notches will be selectively engaged with the periphery of the tub. Then, by means of the adjusting device, the legs are adjusted so that the walls of the notches 65 will bind hard against the tub and secure the

tub firmly in position on the stand, as shown in Fig. 2. During the movement of these parts, the links 11 operate in the cut-outs or slots 13 and, as already described, are guided thereby.

70

75 In Fig. 6, I have shown a modified structure, this involving a reversal of the position of the components constituting the adjusting-device. In other words, the link-connecting block 19 occupies, in this instance, a position below the plane of the pivot-block 20 on which the lugs 21 are pivoted. In consequence, the links 22 are pivotally attached to the legs below the plane of their attachment to the block 20 instead of above 80 it, as in the embodiment first described. By reason of this reversal of the parts, the adjusting-screw 23 is swiveled in the block 19 so that when the screw 23 is rotated, it, by reason of being threaded through the block 20, will raise or lower the block 19, as the case may be; this in turn will operate the links 22; and this will, then, adjust the legs toward or away from each other to diminish or increase the space between the sets of 85 notches 24 at the upper ends of the legs to accommodate tubs of various diameters or to position a tub of selected diameter in a 90 higher or lower plane, as desired.

95 The embodiment illustrated in Fig. 8 differs from the two already described in that those, as shown, include four legs or supports; whereas, in this embodiment, there are only three legs 25, which are pivoted, as at 26, on a triangular-shaped block 27 in 100 which is threaded an adjusting-screw 28 provided at its upper end with a rounded head (not shown) adapted to engage with an apertured, triangular-shaped block or element 29, to which links 30 are pivoted, these 105 also being pivoted, as at 31, to the upper ends of the legs. These latter are provided with notches 32 to receive and hold the lower edge of a tub or the like, as already explained in 110 respect to the other embodiments.

The block 29 is provided with slots or cut-outs 33 to guide and lock the links 30.

115 From the foregoing, it will be understood that, by reason of the provision of the link-connecting element and the components connected thereto and operated thereby, these instrumentalities constitute not only an effective means for adjusting the legs to any required extent and to maintain them rigidly in the position to which they are adjusted; but, also, may constitute an additional support for the bottom of the tub. In other words, if the plane of the block 12 is adjusted coincident with that of the bottom of the tub, the latter may rest thereon and be 120 additionally supported by the same. The provision of the slots or cut-outs in the corners of the connecting-block 12 and the pivoting thereto of the arms or links provide for a rigidity of structure which is desirable in 125 130

a stand of this character. When the block 12 is in its lowered position, the links will occupy a position at the top of the slots—marked 13 in Fig. 5, for instance—and bear 5 against the wall 15 and the edge 16 of the slots, as already described. Thus, there would be a three-point engagement between each link and the block. Even when the block 12 is in a higher plane and the link is 10 not in engagement with the top of the slot, it will, nevertheless, be held rigid by its sliding engagement with the inside surface of the wall 15 and the edge 16 of the slot.

It is a particular desideratum of my 15 structure that a fine degree of adjustment shall be possible so that the legs may be clamped hard against the outer wall of the tub and thereby firmly hold the latter in position on the stand. The adjusting screw, 20 its engagement with the block 12, and the coaction between the block and the legs through the links 11, all contribute to this desirable result. I believe I am the first to provide for an adjusting device of the character herein revealed whereby these desirable 25 results are achieved.

It will be seen that, notwithstanding the presence in the structure of the adjusting-device, the arrangement thereof with respect 30 to the legs is such as to permit the stand, as a whole, to be folded into small compass.

What I claim is:

1. A folding-stand including a plurality of supporting-legs, a pivot-block between the legs and to which the legs are pivotally attached, links pivoted to the legs, a block to which the links are connected and having link-receiving cut-outs, and an adjusting-member threaded into the pivot-block and engageable with the block to which the links 40 are connected.

2. A folding-stand including a plurality of supporting-legs, a pivot-block to which each leg is pivoted intermediate its ends, 45 links pivoted to the legs, a block to which the links are connected alining vertically with but disposed in a plane different from the pivot-block, and an adjusting-member threaded into one of the blocks and engageable with the other to vary their relation. 50

3. A folding-stand including a plurality of supporting-legs, a pivot-block between the legs and pivotally attached thereto, links pivoted to the legs, a block to which the links are connected having a central aperture 55 and link receiving and guiding cut-outs, and an adjusting-member threaded into the pivot-block and having a head on its other end for engagement in said aperture.

In testimony whereof I affix my signature.

HENRY A. HANSEN.
